UNITED STATES PATENT OFFICE

2,643,023

HOSE DRAIN FOR FLOATING ROOF TANKS

Frederick D. Moyer, Chicago, Ill., assignor to Chicago Bridge & Iron Company, a corporation of Illinois

Application May 19, 1951, Serial No. 227,189

9 Claims. (Cl. 220—26)

1

This invention relates to a drain for a floating roof tank and more particularly to a drain utilizing a flexible hose for its entire length which may permit the floating roof to rest on the tank bottom when in its lowermost position.

It has been recognized as desirable to build and thereafter land floating roofs in liquid storage tanks on the bottom of the tank. Ordinarily a number of roof supports extend below the roof proper and maintain the roof several feet above the bottom of the tank even when the tank is empty. Floating roofs have not previously been made to land on the tank bottom for a number of reasons including the necessary provision under the roof for a draining structure. The drain of this invention permits the roof to rest on the bottom of the tank when the tank is empty and also permits ready inspection and replacement of the drain at any time. The drain also permits the floating roof to be constructed directly on the bottom of the tank, thereby reducing the cost of the tank by virtue of the elimination of temporary supports and construction framing.

The invention will be described with relation to an exemplary embodiment thereof illustrated in the accompanying drawings. Of the drawings, Fig. 1 is a vertical sectional view through a floating roof tank showing the drainage means of this invention incorporated therein; Fig. 2 is a fragmentary plan view of the tank illustrated in Fig. 1; Fig. 3 is a sectional view taken as indicated by line 3—3 in Fig. 2; and Fig. 4 is a sectional view taken as indicated by line 4—4 in Fig. 3.

There is illustrated in Fig. 1 a liquid storage tank having side walls 10 joined to a bottom 11 which rests directly upon a prepared grade 12. A floating roof 13 having an outer annular pontoon 14 and a central sump 15 is shown floating within the storage tank upon liquid 16. Since the drain of this invention permits the floating roof 13 to be constructed directly upon the bottom 11 of the tank, the bottom is shaped to conform to the configuration of the bottom deck 17 of the floating roof 13. Thus the plates, pontoons, and other structural members which go to make up the floating roof may be laid out directly on the bottom of the tank during construction. A depressed portion 18 is also provided in the bottom for the reception of the sump 15 centrally located in the floating roof. Ordinarily an annular space 19 is provided about the floating roof between the rim 20 of the roof and the tank shell so that the

2

roof will have clearance for vertical movement within the shell. This space may be sealed so as to prevent loss or contamination of the tank contents by any means desirable (not shown).

5 The floating roof is provided with an upper deck which is sloped in such a way as to direct all precipitation to the central sump 15 from which it must be removed. The drain used to remove the precipitation from the sump is a flexible hose 25 which extends through a metal elbow fitting 26 secured to the bottom 11 of the tank and is connected therewith at a flange 27. A suitable pipe 28 is also connected to the fitting 26 at the flange 27 for conducting the liquid away from the tank site. A bleed line 29 provided with a valve 30 communicates with the interior of the fitting 26 so that accumulated water on the bottom of the tank may be drained from the fitting.

In order that the hose drain 25 will not interfere with the landing of the roof on the bottom of the tank, the hose passes from the drain outlet fitting 26 substantially vertically to an idler sheave 31 mounted within a compartment in the outer pontoon 14 of the roof. From the sheave 31 the hose passes over the top of the roof to a drum 32 mounted near the center of the roof. As best seen in Fig. 4, the upper end 25' of the hose is secured to the end of a metal tube 33 which communicates with the hollow shaft 34 supporting the drum 32. It is intended that the hose 25 may be reeled upon the portion 36 of the drum as the roof rises and falls to maintain only a sufficient uncoiled length of hose to extend from the drum to the outlet fitting 26.

35 The hollow shaft 34 of the drum is supported in tubular bearings 37 and 38, in turn supported by standards 39 and 40 mounted on the deck of the roof. One end of the shaft 34 is blanked off at 41 and the other end 42 communicates with a hose 43 extending to a pump 46 whose suction inlet 47 extends into the sump 15. By blanking off one end of the shaft 34, a single stuffing box 48 is required.

45 The means herein utilized to feed the hose about the drum 32 comprises a cable 50 having its upper end 51 secured above the top of the tank shell upon a framework 52. The cable passes downwardly to the roof and about an idler sheave 53 mounted on the outer pontoon 14 of the roof. The lower end of the cable is secured to the drum to wind about the surface thereof in the space 54. The cable is wound about the drum in a direction opposite to the direction that the hose is wound about the drum so that the drum is caused to rotate whenever the roof moves within

the tank in a vertical direction. If desired, an electrical conduit may be brought into the motor 55 for operating the pump 46 along with the cable 50. A double sheave may be provided at 53 to accommodate the conduit.

The operation of the hose drain is positive and simple and requires no power means other than that to pump the water from the sump into the hose drain. As the roof rises from the bottom of the tank, the hose 25 pulls on the drum 32 to rotate it and unwind therefrom, thus causing the cable 50 to be wound upon the drum. The drum is mounted in bearings which permit it to be easily rotated, putting little strain on the hose itself. As the roof descends within the tank, the cable causes the drain to rotate, thus reeling in the hose 25. Both the hose 25 and cable 50 are taut without substantial stress so that slight movement of the roof will cause rotation of the drum as above described. It will be noted that during the travel of the roof between the bottom and top of the tank, substantially all of the hose drain is accessible from the roof for inspection and the like. The hose may be replaced at any time while the tank is in service by detaching it from the drum and the flange 27 on the outlet fitting and pulling the hose through the fitting 26. The new hose is attached to the upper end 25 of the old hose so as to pull it into position at the same time that the old hose is removed from the tank.

The specific arrangement of the sheaves 31 and 53 herein shown is at diagrammatically opposite points on the roof and the drum and pump are generally at the center of the roof to provide for balancing of the weights on the roof. However, it will be understood that in installations where the distribution of the weight is unimportant the drum 32 may be placed in any other location desired. In some installations the sheave 31 may be eliminated and a cable and drain hose wound directly onto the drum 32 located adjacent the periphery of the roof. Also housings such as the housing 60 over the sheave 31 may be provided over all of the otherwise exposed parts of the drainage system, if desired.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In a storage tank having a floating roof, drainage means for the roof comprising, a drain hose extending between the roof and the tank bottom, a drum rotatably mounted on the roof, the upper portion of said hose being secured to said drum for reeling thereon and the lower end being connected to a drain outlet in the bottom of the tank, means for conducting liquid from the top side of the roof to said drain hose and means for rotating said drum with vertical movement of the roof to maintain said drain hose substantially taut between the tank bottom and the drum.

2. Drainage means as specified in claim 1 in which the drum is mounted on the roof above the bottom thereof and said drain hose extends substantially vertically between the roof and the tank bottom and through an opening in the roof to permit the roof to rest on the bottom of the tank in its lowermost position.

3. Drainage means as specified in claim 1 in

which a cable extends between the roof and the top of the tank shell with the lower portion of said cable being secured to said drum for reeling thereon and the upper end thereof being secured to the tank, said cable and drain hose being oppositely wound on said drum and substantially taut to feed about the drum with vertical movement of the roof.

4. In a liquid storage tank having a floating roof adapted to rest directly on the tank bottom in its lowermost position, drainage means for the roof comprising, a rotatable drum mounted on the roof, a hose drain having its upper portion wound in one direction about the drum, an intermediate portion passing through the roof and its lower end connected to a drain outlet in the bottom of the tank, said hose extending substantially vertically from said outlet to the roof, means for conducting liquid on the roof to said drain hose, a cable having its upper end secured to the top of the tank and its lower portion wound in an opposite direction about the drum, said drain hose and cable being taut whereby rise and fall of the roof feeds said hose and cable about the drum and coils a major portion of the hose on said drum when the roof is resting on the tank bottom.

5. In a liquid storage tank having a floating roof, drainage means for the roof comprising, a flexible drain hose extending substantially vertically between the roof and the tank bottom, a drum rotatably mounted on the upper side of the roof, the upper end of said hose being secured to the drum for reeling the hose upon the drum and the lower end being connected to a drain outlet in the bottom of the tank, said roof having an opening for the hose to pass therethrough, means for conducting liquid from the top side of the deck to said drain hose and cable means extending substantially vertically between the top of the tank and the roof with the upper end of said cable means being secured to the tank and the lower end being secured to the drum for reeling the cable means thereon, said cable means and drain hose being oppositely wound on the drum and each being substantially taut between its secured ends whereby the drain hose is reeled on and off the drum with vertical movement of the roof to maintain an uncoiled length of hose sufficient only to extend from the drum to the drain outlet.

6. Drainage means as specified in claim 5, in which the drum is located at substantially the center of the roof and said drain hose passes from the drum over a sheave adjacent the periphery of the roof and then vertically to the tank bottom, said sheave being mounted in the upper portion of the roof to maintain the portion of the hose between the sheave and drum accessible from the top side of the roof.

7. Drainage means as specified in claim 5, in which the floating roof has a central sump and said drum is mounted on the roof adjacent the sump, said hose and cable means each passing over a sheave mounted on the roof adjacent the periphery thereof.

8. In a liquid storage tank having a floating roof, drainage means for the roof comprising, a flexible drain hose having its lower end connected with a drain outlet in the bottom of the tank, a sheave rotatably mounted on the roof directly above said drain outlet, a drum rotatably mounted on the upper side of the roof adjacent the center thereof, said drain hose extending over said sheave and through the roof and being connected

to said drum for reeling thereon, pump means for conducting liquid from the top side of the roof to said hose, and means for rotating said drum upon vertical movement of the roof to keep the drain hose substantially taut including, a cable secured to the top of the tank shell and extending substantially vertically to the peripheral portion of the roof and then inwardly to said drum, said cable being wound about the drum oppositely to the winding of the hose on the drum and being taut between the tank shell connection and the drum to reel in the hose upon downward movement of the roof within the tank.

9. Drainage means as specified in claim 8 in which the cable passes over a sheave near the periphery of the roof positioned diametrically opposite the sheave over which said hose passes to balance the weight thereof on the roof.

FREDERICK D. MOYER.
